Primary Examiner — Karen S Acker(74) *Attorney, Agent, or Firm* — Millen, White, Zelano, Branigan, P.C.(57) **CLAIM**

The ornamental design for a ribbon flag, as shown and described.

DESCRIPTION

FIG. 1 is a perspective view of the ribbon flag shown in an environment of use.

FIG. 2 is a perspective view of the design of FIG. 1 shown in a second environment of use.

FIG. 3 is a perspective view of the design of FIG. 1 shown in a third environment of use; and,

FIG. 4 is a perspective view of the design of FIG. 1 shown in a fourth environment of use.

The broken lines in the drawings represent environmental subject matter that forms no part of the claimed design.
